UNITED STATES PATENT OFFICE.

GEORGE C. BECK, OF SPOKANE, WASHINGTON.

MACHINE FOR GROOVING PISTON RINGS.

Application filed April 28, 1923. Serial No. 635,296.

To all whom it may concern:

Be it known that I, GEORGE C. BECK, a citizen of the United States, residing at Spokane, in the county of Spokane and 5 State of Washington, have invented new and useful Improvements in Machines for Grooving Piston Rings, of which the following is a specification.

The object of this invention is to provide 10 a novel machine for grooving piston rings.

The trade now presents many types of grooved piston rings all of which are more costly than the un-grooved stock type or plain rings.

15 Therefore, it is an object of this invention to provide a means whereby any dealer or garage owner can provide plain or stock rings with any type of groove or grooves and sell them at a profitable cost far below 20 the price of initially grooved rings.

It is a feature of my improved method and machine to feed a rotating ring to the cutting tool in a direction angular to the axis of rotation of said ring.

25 In one use of my invention, the ring is fed by shifting the ring into a rotative axis parallel with a neutral axis, where it is desired to groove the periphery of the ring. In another use, where it is desired to groove 30 the ring partly on the periphery and partly on a lateral face thereof, I feed the ring to the tool by shifting the ring from a neutral axis into an axis of rotation angular to the neutral axis, and in both instances, I avoid 35 longitudinal adjustment of the shaft mechanism on which the ring is carried.

Other features and objects of the invention will be more fully described in connection with the accompanying drawings and 40 will be more particularly pointed out in and by the appended claims.

In the drawings:

Fig. 1, is a view in side elevation of my machine with parts thereof in section.

45 Fig. 2, is a plan view thereof.

Fig. 3, is a sectional view on line 3-3 of Fig. 1.

Fig. 4, is an end elevation looking from the left of Fig. 1.

50 Fig. 5, is an edge view looking from the right of Fig. 4.

Fig. 6, is an enlarged face view illustrating the means of holding a ring in position.

Fig. 7, is a reverse view of the chuck shown in Fig. 6. 55

Fig. 8, is a detail sectional view on line 8-8 of Fig. 6.

Fig. 9, is a sectional view of a part of a piston ring after being peripherally grooved in accordance with my invention. 60

Fig. 10, is a plan view of the machine, details omitted, showing the ring in a neutral adjustment.

Fig. 11, is a similar view showing how the ring is fed to the tool to cut a groove 65 partly in the periphery and partly on one side face of the ring.

Fig. 12, is a similar view showing the reverse or retractive adjustment.

Fig. 13, is a sectional view of a portion 70 of a piston ring showing the latter provided with a groove partly in the periphery and partly in the side face thereof.

Fig. 14, is a sectional view on line 14-14 of Fig. 10. 75

Like characters of reference designate similar parts throughout the different figures of the drawings.

In the form shown, 1 is the base of a frame which includes alined bearings 2 and 3, which may be split or not, as desired. Snugly fitting the bearings 2 and 3, but rotatively adjustable therein, is a sleeve 4, which is also held against longitudinal movement. An actuator in the form of an arm 5, has at one end a collar 6, which is fast to sleeve 4, as by a pin 7. This collar prevents movement of the sleeve to the left of Fig. 1. Said sleeve 4, is provided with a bore which, as shown in Fig. 3, is eccentric 80 with respect to the periphery of the sleeve and with respect to the axis of bearings 2 and 3. 85

A shaft 8, is journalled in said sleeve 4, and said shaft projects beyond the right 95 hand end of said sleeve, viewing Fig. 1, sufficiently to carry the hub 9, of a crank 10, for rotating said shaft 8. On the opposite end of shaft 8, is rigidly mounted a ring holder which is shown in the form of a disc 11. The hub 12, of said disc, coacting with bearing 2, prevents the shaft 8, from moving to the right, of Fig. 1. The base 1, is suitably slotted at 13, to permit the disc to project therein. 100

Said disc has a plurality of radially dis-

posed slots 14, suitably undercut, as at 15, and radially adjustable in each of said slots is a centering lug 16. I prefer to employ a counter-sunk screw 17, to extend through the lug 16, and through the corresponding slot 14, a nut on the rear end of said screw fits snugly in the under-cut portion 15. Hence, it is merely necessary to turn the head of the screw with a screw driver to 10 loosen or tighten the lug. In order to prevent the lug 16, itself, from turning, I provide the same with an inturned retainer 18, which extends into the slot 14. These lugs 16, project from the working face 19, of the disc 11, sufficiently to engage the periphery 20, of the piston ring 21. I preferably concave the inner ends 22, of said lugs, so that they will have a greater bearing engagement with the ring. It will be clear that the 20 piston ring 21 is disposed flat against the disc 11.

I will next describe the novel means for centering and clamping the ring in position on the disc 11.

25 I employ a clamping chuck which includes a chuck plate 23, having a centering hole 24, therein, adapted to fit over a threaded centering pin 25, of disc 11. Said plate 23, is provided with pairs of slots 26 and 27, opening through the ends of said plate. On the rear face of said plate is a pair of clamping strips 28 and 29, of like construction, the same being longitudinally adjustable with respect to plate 23, to project the ends 35 of said strips beyond the ends of said plate, a distance dependent upon the size of ring to be clamped. Strip 28, is adjustably held by screws 30, and strip 29 by screws 31. The strips 28 and 29 may be suitably graduated, 40 as shown in Fig. 6, to register with the corresponding ends of plate 23, to determine the extent of projection of said strips. It will be seen that the projecting ends of the strips 28 and 29, clamp against the outer 45 face of the ring 21. A nut 32, is turned onto stem 25, and against plate 23, to clamp the strip ends tightly against the ring.

Before the ring 21, is positioned, the strips are adjusted so that their opposite ends will 50 form a dimension equal to the outer diameter of the ring to be grooved. By turning the chuck on stem 25, with the ends of the strips opposite slots 14, the lugs 16, can be radially adjusted into registry with the strip 55 ends so that when the ring, which is split, is contracted to dispose its split ends in abutting relation, the ring will fit snugly between the centering lugs 16. This centers the ring with respect to the rotating disc 11. Then 60 the screws 18, are tightened. I next turn nut 32, against the plate 23, as before stated.

The ring is now centered and securely clamped in position with the outer portion of its periphery exposed for action by the 65 cutting tool, as clearly seen in Figs. 5 and

8. If more than one groove is to be formed, as shown in Fig. 9, then, the ring will be taken off, and its position reversed, side to side, with respect to disc 11, to expose the remaining peripheral portion.

I will next describe the means for holding a cutting tool in workable relation to the centered ring, and the manner in which the ring is fed to the tool.

70 The base 1, is provided with a slot 33. A tool holding standard 34, has a base 35, resting on base 1, above slot 33. Screws 36, having relatively large washers 37, extend through slot 33, into base 35, the heads 38 engaging said washers 37. The screws 36, 75 are so reduced in size with respect to said slot 33, that the standard can be universally adjusted along the plane of base 1, to any desired position. The top of standard 34, is reduced at 39, forming a fulcruming ledge 80 85 40. A tool holding plate 41, has one side resting on ledge 40, the opposite edge resting on a tool 42. Screws 43, serve to clamp the plate 41, tightly onto said tool 42, holding the latter rigidly in position. The space afforded permits the tool 42, to be disposed at any required angle in the tool holder. When grooving the periphery of a ring, the tool 42, would be disposed substantially as 90 shown in Figs. 1 and 2, but when grooving a ring laterally, the tool would be disposed substantially as shown in Figs. 10 to 12.

95 Next referring to Figs. 1 and 3, and assuming that the grooving operation is about to start, it will be seen that in this particular form, the lever arm 5, is in a vertical position, and hence, the shaft 8, is in a neutral adjustment. In this adjustment, the thickness of the sleeve is the same on both lateral 100 diametrical points, viewing Fig. 3. Now, to advance the ring toward the cutting tool, the user will gradually shift the lever in the direction of arrow A, of Fig. 3, thereby disposing the thicker portion of the sleeve 4, to the right of shaft 8, viewing Fig. 3. The ring is advanced until the groove is cut to the required depth. In retracting the 105 ring from the cutting tool, the lever will be shifted to the right of Fig. 3; or in the direction of arrow B. In the use of sleeve 4, it 110 will be seen that the shaft 8, or rather its axis, is always in parallel relation with the longitudinal periphery of sleeve 4; or in other words, in parallel relation with the 115 axis of bearings 2 and 3, and never in angular relation therewith. This is sufficient for the performance of the function desired, namely, to groove the periphery of the ring, which requires a shift of the disc laterally in the plane in which the disc is rotating. In other words, there is no longitudinal movement of the shaft 8, or of the disc 11, along the length of shaft 8, because only a lateral 120 feed is required.

125 130 However, assuming that it was desired to

form a groove partly in the periphery and partly in one side face of the ring, as shown in Fig. 13, then, something more than a mere lateral feeding movement is required. The 5 tool 42, is disposed in its holder, previously described, in the required angle, as shown in Figs. 10 to 12. Instead of using sleeve 4, with its bore in parallel eccentricity with the sleeve, I employ a sleeve as indicated 10 to 44, having a bore which is not only eccentrically disposed but in angular relation to the axis of sleeve 44. Not only is this bore in eccentric angular relation to the 15 axis sleeve 44, but its angular disposition is of a novel type or form, as will presently appear.

It is desired to state that Figs. 10 to 12, do not show a modification of the form shown in Fig. 1. The two forms are identical in structure and operation except for the difference in the bore of sleeve 44, and the consequent difference of operation resulting therefrom. In other words, I have 20 presented a machine, which is an entity, and 25 I have presented two forms of sleeves, either of which may be employed in the machine, in accordance with the work to be performed.

Now assuming that the parts are in 30 readiness for forming a groove of the type shown at 45, and the machine in plan, is in the position shown in Fig. 10, it will be clear that the ring 46, must not only be fed radially of the neutral axis C, but also 35 angularly, or broadly speaking, that portion of the ring 46, in actual contact with tool 42, must be fed longitudinally of shaft 8. Hence, in Fig. 11, I have shown the lever 5, shifted to feed the ring 46, to the full 40 depth of the groove 45, to be formed, and in Fig. 12, I have shown the lever 5 having been shifted in the opposite direction to retract the ring from the tool 42. Now, the neutral axis C, is also, viewing the machine 45 in plan, the axis of the bearings 2 and 3. However, the axis of the bore of sleeve 44, is indicated at D. It will be seen that axis D, does not intersect with axis C, until point 50 E, is reached. If it intersected to the right of disc 11, viewing Figs. 10 to 12, then, the dual movement of the ring toward the tool, namely the radial and angular movement would not result. It will now be clear, that I 55 specifically do more than dispose the axes C and D in angular eccentric-relation, I dispose axis D, in lateral or converging relation to axis C, throughout the length of shaft 8, and with the said axes more closely adjacent nearest disc 11, than remote there- 60 from. As shown in Fig. 14, the neutral axis C, may not coincide with the axis of bearings 2 and 3, in some constructions, dependent on the extent of angularity of the bore of sleeve 44. However, in any 65 event, as regards this specific disclosure, the

disc 11, will be at right angles to the axis of bearings 2 and 3, when the sleeve 44 is in the neutral adjustment shown in Fig. 10.

I wish to assert as new, as an article of manufacture, a sleeve for a machine of this 70 character, having a bore in parallel eccentricity therewith, and a sleeve having a bore in angular eccentricity therewith, and further, a sleeve having a bore in substantially the eccentric angular relation thereto 75 as shown in Figs. 11 and 12.

I do not wish to be limited to the disclosure herein made, except for such limitations as the claims may import.

I claim:—

1. A machine for grooving a piston ring, comprising a bearing, a sleeve rotatably adjustable in said bearing and having a bore eccentric to the periphery of said sleeve, a rotatable shaft journalled in said bore, a ring holder carried by said shaft, means for holding a cutting tool in workable relation to the ring held by said holder, and means for rotatably adjusting said sleeve to advance or retract the ring toward or from 90 said tool while said shaft is being rotated.

2. A machine for grooving a piston ring, comprising a bearing, a sleeve rotatably adjustable in said bearing and having a bore in parallel eccentricity to the periphery of 95 said sleeve, a rotatable shaft journalled in said bore, a ring holder carried by said shaft, means for holding a cutting tool in workable relation to the ring held by said holder, and means for rotatably adjusting 100 said sleeve to cause said shaft to rotate about an axis concentric with the periphery of said sleeve or parallel thereto to advance or retract the ring toward or from said tool.

3. A machine for grooving a piston ring, comprising a bearing, a sleeve rotatably adjustable in said bearing and having a bore, a shaft journalled in said bore, a ring holder carried by said shaft, means for holding a cutting tool in workable relation to the ring held by said holder, the bore in said sleeve being in such angular eccentricity to the axis of said bearing as to intersect said bearing axis at a point endwise of 110 said sleeve and beyond the cutting path of said tool, and means for rotatably adjusting said sleeve to advance the ring laterally and radially toward said tool.

4. A machine for grooving a piston ring, 120 comprising a bearing having a bore, a sleeve journalled in said bearing and having a bore, a shaft journalled in the bore of said sleeve, a ring holding disc carried on one end of said shaft beyond said sleeve, 125 means for holding a cutting tool in angular relation to the plane of rotation of said disc and in workable relation to said ring, the bore in said sleeve being in such angular eccentricity to the axis of said bearing as 130

to intersect said bearing axis at a point endwise of said sleeve and beyond said disc and said eccentricity being greater at that end of said sleeve remote from said disc than 5 adjacent thereto.

5. A machine for grooving a piston ring, comprising a rotatable disc having radial slots and a threaded centering pin, centering lugs adjustable in said slots for engaging the 10 periphery of the ring, a graduated chuck centered on said pin and adjustable to different radial lengths for locating said lugs, and a nut on said pin for clamping said chuck against the outer face of the ring, 15 and means for holding a cutting tool in workable relation to said ring.

6. A machine for grooving a piston ring, comprising a rotatable disc having means for centering the ring against the face of the 20 disc, means for clamping the ring in place against said disc, and means for holding a

cutting tool in workable relation with said ring, and means for shifting said rotating disc to feed the ring toward said tool.

7. A machine for grooving a piston ring, 25 comprising a base having aligned bearings, a sleeve rotatably adjustable in said bearings and having a bore eccentric to the axis of said bearings, a disc on one end of said shaft provided with means for holding a piston ring against its face, a tool holder universally adjustable in one plane on said base for holding a tool in workable relation to said ring, a lever on that end of said sleeve remote from said disc end for adjusting said sleeve to feed the ring to said tool, and a crank on that end of said shaft 30 remote from said disc for rotating the latter.

In testimony that I claim the foregoing as my own, I hereby affix my signature.

GEORGE C. BECK.
